UNITED STATES PATENT OFFICE.

THEODORE H. BARTMANN, OF BROOKLYN, NEW YORK.

DESIGN FOR A PORTIÈRE OR CURTAIN.

SPECIFICATION forming part of Design No. 21,389, dated March 8, 1892.

Application filed February 8, 1892. Serial No. 420,600. Term of patent 3½ years.

To all whom it may concern:

Be it known that I, THEODORE H. BARTMANN, a citizen of the United States, and a resident of Brooklyn, in the county of Kings 5 and State of New York, have invented a certain new and original Design for Portières and Curtains, of which the following is a specification.

The accompanying drawing shows a face 10 view of part of a portière of my new design.

The essential features of my new design consist of a central field and a serrated border for the same, a row of approximately diamond-shaped openings separated by bunches 15 of gathered strands along the serrated longitudinal border of the central field, and a similar row parallel with the first and extending to the end of the portière.

A is a central field.

B is the serrated border on all four sides of 20 the field, the serrations extending into the field A.

C is a row of alternating approximately diamond-shaped openings *a* and bunches *b* of gathered strands, which row extends along 25 the longitudinal serrated borders.

D is a row like the row C a short distance from and parallel with the same, both rows extending to the ends of the portière.

E are tassels on the ends of the portière. 30 Having thus described my design, what I claim as new, and desire to secure by Letters Patent, is—

The design for portières and curtains, substantially as herein shown and described. 35

In testimony that I claim the foregoing as my invention I have signed my name in presence of two subscribing witnesses.

THEODORE H. BARTMANN.
